ACHILLE DRYEN, OF TUBIZE, BELGIUM, ASSIGNOR TO SOCIETE ANONYME FABRIQUE DE SOIE ARTIFICIELLE DE TUBIZE, OF TUBIZE, BELGIUM.

METHOD FOR THE CONCENTRATION OF SULFURIC ACID.

1,323,847.

Specification of Letters Patent.

Patented Dec. 2, 1919.

Application filed June 25, 1915. Serial No. 36,190.

To all whom it may concern:

Be it known that I, ACHILLE DRYEN, a subject of the King of Belgium, residing at Tubize, in the Kingdom of Belgium, have 5 invented certain new and useful Improvements in Methods for the Concentration of Sulfuric Acid, of which the following is a specification.

My invention relates to improvements in 10 the methods, and apparatus therefor, as are used for the concentration of sulfuric acid and more particularly to the methods in which is made use of a number or series of evaporating elements which are arranged in 15 a stepped order and communicate with one another in such a manner that the acid flows from the uppermost to the lowermost element while the vapors, which are produced by the ebullition of the acid under the action 20 of a source of heat acting from outside, pass from the lowermost to the uppermost element of the series.

My invention has for its object to secure 25 a more perfect utilization of the heat contained in the vapors which are produced, than has been hitherto obtained and further to reduce to a minimum the disengagement of sulfuric acid.

With these objects in view, my invention 30 essentially consists in sending the vapors, which are set free in each of the elements, into the mass of liquid which is to be concentrated so as to utilize the heat contained in said vapors (and which is set free by their condensation), for the production of a new quantity of vapor at a lower temperature and having less sulfuric acid than the vapors coming from the evaporating elements.

The annexed drawing shows diagrammatically by way of example, a vertical section through an apparatus suitable for carrying my invention into practice.

The apparatus comprises a number of closed elements *a* of suitable material such 45 as cast-iron adapted to resist the action of acids or platinum (especially for strong acids) or ordinarily lead (for weak acids).

The said elements are arranged in stepped order, as shown in the drawing and communicate with one another through pipes *b*, securing the circulation of the acid and maintaining a constant level in each element.

The lowermost element of the series is 50 provided with a conduit *c* for the flowing out of the concentrated acid and the uppermost element is connected by a conduit *d* to

a heater for the acid which is to be fed to the elements. The several elements, three in the example shown, are further connected with each other by conduits *f* which are 60 provided in order to conduct the vapors generated in a given element to the next upper element. As shown on the drawing, each of the conduits *f* opens in the next upper element beneath the level of the acid contained 65 in the latter element. The uppermost element, which is fed with sulfuric acid through the conduit *d*, is connected by a conduit *g* to a tubular heater or coil *h* adapted to heat the acid which is to be concentrated. 70 Said tubular heater or coil *h* is connected to a second coil *i* placed in a cooling-vat *j* provided with connections *k* for a water-circulation. The whole of the apparatus is arranged in such a manner that the concentrating elements *a* present the greatest surface 75 possible to the action of heating gas produced in a furnace *l* or to any other heating medium.

When the apparatus is in action, the acid 80 which is to be concentrated, flows from the heater *e* through the conduit *d* into the uppermost element *a* of the series of elements and thence flows successively, in a descending course, through the conduits *b* in the different elements composing the apparatus and escapes finally through the conduit *c*. The vapors which are produced in the lowermost element are conducted through the conduit *f* in the next upper element where 90 they are led, as shown by the arrow into the mass of liquid contained in said element. Again the vapors produced in the second element of the series are similarly conducted in the third element of the series into the mass 95 of liquid contained therein, and so on. Finally the vapors produced in the last or uppermost element of the series are conducted through the conduit *g* into the coil *h* of the heater *e* where they are condensed 100 and afterward cooled when circulating in the coil *i* of the cooling vat *j*.

It will be observed, consequently that the mixture of vapors of sulfuric acid and water, which is produced in a given element, is 105 always conducted into a liquid mixture of sulfuric acid and water having less strength or concentration than the mixture which has produced the said vapors. A condensation of the vapor of sulfuric acid takes place consequently and the heat which is set free by this modification of state, again secures the 110

vaporization of a certain quantity of water. If a condensation of a certain quantity of water-vapor also takes place, the heat of condensation of said vapor and the heat due 5 to the reaction between said water of condensation and the sulfuric acid are equivalent to the quantity of heat which is necessary for the re-separation of a corresponding quantity of water and its reëvaporation 10 with this difference, however that the new vapors, which are produced have a temperature which is lower than that of the first mentioned vapors.

As a result, the vapors which are produced in a lower element, owing to the fact 15 that they are conducted into the mass of liquid contained in the next upper element, are replaced by a corresponding quantity of vapors having a lower temperature and less 20 sulfuric acid than themselves. But as the temperature of the vapors which are produced in a given element, is considerably lower than the boiling temperature of the liquid, the temperature of the vapors passing 25 through the mass of liquid contained in the next upper element, may be lower than the boiling temperature of said liquid. On the other hand, the vaporization of any 30 quantity of water, other than that corresponding to the condensation of the vapors coming from the preceding element, requires not only the evaporating heat but also 35 a new quantity of heat which is equivalent to the heat of reaction between sulfuric acid and water.

Said quantity of heat which is necessary to secure a concentration in the next element, is furnished by the furnace *l* or by any other source of heat, for instance by coils heated 40 by gas or vapor at a suitable temperature.

These theoretical considerations show that the economical utilization of the heat contained in the vapors which are set free and the condensation of the sulfuric acid 45 contained in said vapors, are not necessarily bound to the passage of the vapors which are produced in a given element, into the mass of liquid contained in the next upper element but that a similar result could be 50 obtained by collecting together the vapors which are produced in the different elements of the apparatus and then leading said vapors conjointly in the uppermost element in which the sulfuric acid is led for the 55 purpose of concentration.

Each of the elements composing the apparatus could evidently be subdivided in a number of compartments arranged in stepped order so as to increase the number 60 of passages or bubbling of the vapors through the mass of liquid contained in each element.

Having thus described my invention, what I claim is:

65 1. A method of concentrating sulfuric

acid, which comprises heating separate volumes of acid confined against direct contact with the products of combustion of the source of heat, conducting the vapor produced by each volume of acid into acid of less concentration, the contact of the vapor with the acid of less concentration causing the evolution of vapor containing less sulfuric acid than the vapor of the acid of higher concentration and conducting acid 75 from one volume to the volume of acid of greater concentration.

2. In an apparatus for concentrating sulfuric acid, a series of closed vessels each adapted to hold sulfuric acid of a different 80 degree of concentration, means for heating each of said vessels, conduits connecting said vessels for conducting the sulfuric acid from one vessel to the next vessel containing sulfuric acid of a greater degree of concentration, and conduits connecting said vessels for conducting the vapors given off in each vessel to the next vessel into sulfuric acid of a less degree of concentration, the conduits and vessels maintaining the acid and vapors 90 out of contact with the products of combustion of the heating means.

3. In an apparatus for concentrating sulfuric acid, a series of closed vessels each adapted to hold sulfuric acid of a different 95 degree of concentration, means for heating each of said vessels, conduits connecting said vessels for conducting the sulfuric acid from one vessel to the next vessel containing sulfuric acid of a greater degree of concentration, conduits connecting said vessels for conducting the vapors given off in each vessel to the next vessel into sulfuric acid of a less degree of concentration, a conduit for conducting weak sulfuric acid to the first 100 vessel of said series, a heating coil, and means for conducting the vapors from said first named vessel to said heating coil and said heating coil being arranged to heat the weak sulfuric acid in said conduit.

4. A method of concentrating sulfuric acid which comprises heating several volumes of acid to the boiling point, maintaining the acid out of contact with the products of combustion of the source of heat, conducting the vapor produced by each volume of acid into acid of less concentration, the contact of the vapor with the acid of less concentration causing the evolution of vapor containing less sulfuric acid than the vapor of the acid of higher concentration, and conducting acid from one volume to the volume of acid of greater concentration.

In testimony whereof I have affixed my signature in presence of two witnesses.
